TAG

Mervin Levine, New York, and Jesse Levine, Great Neck, N. Y., assignors to Susquehanna Waist Company, Upland, Pa., a corporation of Pennsylvania

Application September 11, 1953, Serial No. 26,772

Term of patent 14 years

(Cl. D1—12)

To all whom it may concern:

Be it known that we, Mervin Levine and Jesse Levine, citizens of the United States, residing respectively at New York, county of New York, and Great Neck, county of Nassau, both in the State of New York, have invented a new, original, and ornamental Design for a Tag, of which the following is a specification, reference being had to the accompanying drawing, forming a part thereof.

In the said drawing Fig. 1 is a front elevation of a tag embodying our new design; and

Fig. 2 is a side elevation thereof looking at the tag from the left in Fig. 1.

The characteristic features of the design reside in the portions shown in full lines.

We claim:

The ornamental design for a tag, substantially as shown and described.
